UNITED STATES PATENT OFFICE.

EARL M. WITHERELL, OF DULUTH, MINNESOTA, ASSIGNOR OF ONE-HALF TO F. A. PATRICK & COMPANY, OF DULUTH, MINNESOTA, A CORPORATION OF MINNESOTA.

YARN STAND FOR KNITTING MACHINES.

Application filed September 17, 1921. Serial No. 501,290.

To all whom it may concern:

Be it known that I, EARL M. WITHERELL, a citizen of the United States, residing at Duluth, in the county of St. Louis and State 5 of Minnesota, have invented certain new and useful Improvements in Yarn Stands for Knitting Machines, of which the following is a specification, reference being had therein to the accompanying drawing.

10 This invention relates to knitting machines and has special reference to an improved yarn stand for what is known as flat knitting machines. Those familiar with the art know that in the ordinary flat knitting 15 machine the yarn stand is a permanent fixture extending horizontally away from and in front of the operator of the machine, and in the use of such machines when it becomes necessary to change the color or quality of 20 yarn being used the machine must be stopped and the bobbins or spools of yarn changed upon the stand and the machine re-threaded accordingly, all of which necessitates the inactivity of the machine and the operator, 25 unless his time be spent in making the necessary changes.

The principal object of my present invention is to provide an adjustable multiple 30 yarn stand which may be quickly adjusted to or from active position on the machine and the latter quickly re-threaded without necessitating a material delay in the operation of the machine.

Another object of the invention is to provide 35 means whereby a second party, other than the operator, may attend to the changing or replenishing of the yarn stand while the machine is in operation.

Other objects and advantages of the invention will appear in the further description thereof.

Referring to the accompanying drawing wherein like reference characters indicate like parts,

45 Figure 1 represents a rear elevation of one embodiment of the invention, and

Figure 2 is an end elevation of the same.

1 represents the base of a flat knitting machine, and 2 a suggestion of the ordinary 50 needle bed.

The yarn stand is supported upon two up-standing brackets 3 which are securely bolted to the rearmost edge of the base 1, as at 4, and, in Figure 2, I have illustrated at 5, in 55 dotted lines, the position of the ordinary

yarn stand which may or may not be dispensed with in making use of my improved stand, as the improved stand operates above same and wholly independently thereof, though, of course, the bobbins or spool 60 spindles in the ordinary stand would have to be removed if my improved stand were applied to such machine.

In the ordinary machine of this type there are two upright rods 6 and 7 which form 65 extensions of the brackets 3, and connecting the two ends of these upright rods, extending longitudinally of the machine, is a bar 8, this ordinarily being for the support of the take up brackets 9, the location of which, 70 however, are entirely changed where my improved yarn stand is installed.

In the installation of the multiple yarn stand, I provide two rectangularly shaped metal fabricated structures, indicated at 10 75 and 11, they being preferably of light angle iron and made of sufficiently staunch structure in any desired manner. These frames are pivotally hung one upon each one of the upright rods 6 and 7, they being provided 80 for such pivotal suspension with angle clips 12 securely fixed to one corner thereof and having holes therethrough which surround the upright rods, and a collar 13 is securely fixed to each rod 6 and 7 just beneath the 85 lowermost supporting angle clip 12 so that in this manner each stand may be swung backwardly away from the cross bar 8 or towards and against same as the exigency of the case demands. A small metal clip 14 is 90 attached adjacent the upper innermost corner of the free end of each stand and which clip is provided with a concaved notch in the lower edge thereof for the purpose of overlapping or hooking over the upper edge 95 of the cross bar 8 when the rack is swung into active position on the machine and is also for the purpose of holding said rack in such position.

Upon each rack is mounted the usual number of spaced cone or bobbin spindles 15, upon which any desired number of spools of yarn may be applied and threaded in the usual way except that I prefer to make the spindles 15 in the two uppermost series 100 low so that the threads from the lower spindles may pass therethrough and be joined with their companion threads in the upper part of the stand as desired, and that the take up brackets 9 are carried upon the 110

uppermost inner edge of each stand so that each stand is provided with its own set of take up brackets.

As an additional novel feature in connection with this form of multiple yarn stand I propose to use a job or work card indicated at 16 which is hung upon one corner of each yarn stand so that the job foreman, having a knowledge of the subsequent requirements 10 of the machine, may place a card thereupon when not in use for the information and guidance of the party furnishing yarn to the stand so that he may proceed to fill the unoccupied stand ready for instant change by 15 the operator when the time arrives for him to make such change in the work being accomplished so that all he has to do is to swing out of operative position the stand which he has been using and swing the other 20 stand into place and tie in his threads.

From the foregoing it is evident that I have devised novel means whereby to mate-

rially increase the efficiency of a flat knitting machine upon which frequent changes of yarn is made.

Having thus described my invention what I claim and desire to secure by Letters Patent, is:

The combination with a flat knitting machine of the character described having an upright frame structure on the bed thereof, of a yarn stand or rack pivotally mounted at each end of said frame, take up brackets carried by each stand, and bobbin spindles carried by each stand whereby one of the 30 stands may be replenished or supplied with yarn while the other is in operative engagement with the machine.

In testimony whereof I hereunto affix my signature in the presence of two witnesses. 40

EARL M. WITHERELL.
